UNITED STATES PATENT OFFICE

LOUIS H. KAL, OF KALAMAZOO, MICHIGAN, ASSIGNOR TO SHAKESPEARE PRODUCTS COMPANY, OF KALAMAZOO, MICHIGAN

CONTROL DEVICE

Application filed March 7, 1930. Serial No. 433,885.

The main object of this invention is to provide a control device for choke valves for carburetors and other remote controls which is well adapted for retaining the parts in their adjusted positions.

A further object is to provide a structure having these advantages which is very simple and economical in its parts and the parts are so arranged and supported as to prevent rattling.

Objects pertaining to details and economies of my invention will definitely appear from the description to follow. The invention is defined in the claims.

15 A structure embodying the features of my invention is clearly illustrated in the accompanying drawings, in which:

Fig. 1 is a fragmentary view mainly in longitudinal section of a choke valve control 20 embodying the features of my invention, the section being on line 1—1 of Figs. 2 and 3.

Fig. 2 is a transverse section on line 2—2 of Figs. 1 and 3.

Fig. 3 is a plan view of one of the support 25 members.

Fig. 4 is a face view of the finger piece.

Referring to the drawing, we provide a tubular support preferably made up of the section 1 externally threaded at 2 to facilitate 30 mounting in an instrument board or the like of a motor vehicle. The section 3 is telescoped with the section 2, these parts being secured together and, in effect, constituting a single element made of sections for convenience in manufacture.

35 4 represents the sheath or housing for the push rod 5 leading to the part operated which is not here illustrated. The parts 2 and 3 of the support being of different internal diameters provides the support with a stepped bore.

The headpiece 6 is reciprocatingly mounted in the support and is a sliding fit in the reduced section of the support, the rod 5 being arranged in a longitudinal bore 7 in the headpiece and secured therein by offsetting at 8. The headpiece is provided with a finger-piece 9 preferably having the word "Choke" 40 thereon, although it is to be understood that

this legend would be in accordance with the part to be operated.

The headpiece 6 has a longitudinal groove 10 therein which is engaged by the bowed spring 11. This spring has a laterally turned end 12 engaging the radial bore 13 in the support, thereby anchoring the spring. The other end of the spring is in supporting engagement with the wall of the reduced portion of the bore, the spring being thus held under tension and also locked in position. The friction of the spring and the friction caused by the spring pressing the headpiece against the wall of the support holds the headpiece in its adjusted position and also 60 prevents rattling. Further, the spring engaging the groove holds the headpiece against rotative movement so that the legend is properly presented.

65 The parts of my improved control device 70 are very economical and very quickly and easily assembled. The spring is held in assembled position without riveting or otherwise securing than by engaging its laterally turned end in the hole 13 and inserting the 75 headpiece.

I have illustrated and described my improvements in the form designed by me for use as a carburetor choke although it is adapted for use in various other relations. It 80 is believed that such other adaptations will be readily understood by those skilled in the art to which the invention relates.

Having thus described my invention what I claim as new and desire to secure by Letters Patent is:

1. A control device comprising a tubular support having a stepped bore and a radial bore in the wall of the larger portion thereof, a cylindrical longitudinally grooved head piece reciprocatingly mounted in said support and provided with a finger piece at its outer end, and a bowed spring disposed within said support in engagement with said groove in said head piece and having an outerturned part at one end disposed in said radial bore in the wall of said tubular support, its other end being in engagement with the wall of the reduced portion of said bore, whereby said spring is retained in position under ten- 100

sion and said head piece is frictionally retained in its adjusted positions and supported against rotative movement and rattling within the support.

5 2. A control device comprising a tubular support having a radial hole in the wall thereof, a longitudinally grooved head piece reciprocatingly mounted in said support and provided with a finger piece at its outer 10 end, and a bowed spring disposed within said support in engagement with said groove in said head piece and having an anchoring part at one end engaging said radial hole in the wall of said tubular support, its other end 15 having the upward movement thereof limited by the wall of said tubular support.

3. A control device comprising a tubular support having a stepped bore, a head piece reciprocatingly mounted in said bore and 20 having a longitudinal groove therein, and a bowed spring disposed within said bore in engagement with said groove with one end anchored to the wall of the enlarged portion of the bore and its other end having the outward movement thereof limited by the wall of the reduced portion of the bore.

4. A control device comprising a barrel-like support, a head piece having a longitudinal groove therein reciprocatingly mounted 30 in said support, and a bowed spring mounted within said support to engage said groove and anchored at one end to the wall of the support and having its other end in upward movement limiting contact with the wall of 35 the support.

5. A control device comprising a barrel-like support, a head piece reciprocatingly mounted in said support, and a bowed spring mounted within said support to engage one 40 side of said head piece and anchored at one end to the wall of the support and having its other end engaging the inner surface of the wall of the support.

In witness whereof I have hereunto set my
45 hand.

LOUIS H. KAI.
